UNITED STATES PATENT OFFICE

FRANK R. BELLUCHE, OF RACINE, WISCONSIN

PRINTING PRESS

Application filed October 19, 1929. Serial No. 400,843.

This invention relates to certain new and useful improvements in printing presses and refers more particularly to multi-color presses.

Heretofore, all of the color units of multi-color presses have been connected with, and simultaneously driven by a common means. With this construction it is obvious that only one unit could be made ready at one time, and as a press, during make-ready, is idle from a production standpoint, the excessive time required for this operation was costly. The time required for make-ready in such presses has been approximately 40% of the normal operating time leaving but 60% of the time for actual printing or productive work.

Make-ready has also been exceptionally difficult in conventional multi-color presses, due to the necessity of the plates of the different plate cylinders being exactly in line as to side and front register. Poor register was also caused in some presses by the transfer of sheets from one cylinder to another between colors.

It is therefore an object of this invention to provide a multi-color press in which the time required for make-ready is reduced to that required for a single color press.

This is accomplished by the provision of an individual drive motor for each color unit of the press, and means whereby the different motors may be connected together to provide a simultaneous drive for all of the units, or may be left separate to permit each unit to be driven independent of the others.

Another object of this invention is to provide perfect register between the different colors, and to obviate the necessity of lining up the different plates as to front and side register by aligning the sheet with the plate of the second color unit as it leaves the first color unit.

With the above and other objects in view which will appear as the description proceeds, my invention resides in the novel construction, combination and arrangement of parts substantially as hereinafter described and more particularly defined by the appended claim, it being understood that such changes in the precise embodiment of the hereindis-

closed invention may be made as come within the scope of the claim.

In the accompanying drawings, I have illustrated one complete example of the physical embodiment of my invention constructed according to the best mode I have so far devised for the practical application of the principles thereof, and in which:

Figure 1 is a diagrammatic view of a two color printing press embodying my invention;

Figure 2 is a diagrammatic view of the electrical control circuit;

Figure 3 is a fragmentary enlarged view of the clutch between the drive shafts of the two units;

Figure 4 is a detail view illustrating a modified clutch structure for coupling the drive shafts; and

Figure 5 is a cross sectional view taken through Figure 4 on the plane of the line 5—5.

Referring now more particularly to the accompanying drawings, the numeral 5 represents the first color unit or section and 6 the second color unit arranged to receive the sheets as they leave the unit 5. Each unit 5 and 6 comprises plate cylinders 7, impression cylinders 8, and delivery cylinders 9. Conventional inking mechanisms 10 are provided for each color unit to ink the plates, not shown, carried by the plate cylinder 7 in the well known manner.

In operation the sheet is fed into the unit 5 either automatically or manually by being placed on a feed board 11 having a front stop 12 and side registers 13 which center the sheet with respect to the plate carried by the plate cylinder 7, to be picked up by grippers 14 carried by the impression cylinder 8. The grippers 14 carry the sheet through the unit 5 and as it passes beneath the plate cylinder 7 the first color is printed thereon.

From the impression cylinder 8 the sheet is transferred to the delivery cylinder 9 being picked up by grippers 15 carried by gripper bars not shown, forming part of a conveyor chain 16. The grippers 15 of the conveyor chain then carry the sheet from the unit 5 and deposit it upon a tape conveyor 17.

which feeds the sheet to the front guides or stops 23 of the second unit 6.

The tape conveyor 17 is of conventional construction including tapes 18 trained about rolls 19 and 20, and sticks 21 disposed between the adjacent tapes. When on the tape conveyor 17 the sheet is "slowed down" by a conventional "slow down" roll 22 intermittently engageable with a roll 22' travelling at a slower speed than the tapes 18. The engagement of the roll 22 with the roll 22' at the time when a sheet is positioned therebetween retards the forward movement of the sheet as is well known in the art.

Prior to entering the unit 6, the sheet again passes between side registers 24 to be properly aligned with the plate of the second color unit. The process of printing which takes place in the second unit 6 is identical to that described in connection with the unit 5, and after the sheet has been printed with the second color it is picked up by the delivery conveyor chain grippers 15 of the unit 6 which carry the sheet either to a third color unit or to a suitable delivery platform, not shown.

Each unit has a pinion 25 which meshes with a gear 26 connected with its impression cylinder. The gears 26 impart the driving action of the pinions to the plate cylinders 7 through gears 27 and to the delivery cylinders through gears 28. The pinions 25 are each driven from shafts 29 by chains 30 or the like, and the shafts 29 are drivingly connected with longitudinal axially aligned shafts 31 through bevel gears 32.

The shafts 31 are suitably journaled in bearings 33 and have clutch members 34 fixed to their adjacent ends by which they may be rigidly connected to insure synchronized operation of the two units. In the present instance, the clutch members consist of flanges 35 adapted to be secured together by bolts 36. Each shaft 31 also has a drive sprocket 37 fixed thereto between its clutch member and the adjacent bearing 33, to be drivingly connected with motors 38 through drive chains 39 or the like.

When the clutch members are secured together it is obvious that the shafts 31 are rigidly connected and inasmuch as the motors 38 are identical as to speed and horse power ratings, it follows, that both units 5 and 6 are simultaneously driven in step with each other. However, when it is necessary to prepare the press for new work, which in the art is known as make-ready, the bolts 36 are removed so that one unit may be driven independent of the other.

During make-ready the outer end 40 of the delivery mechanism which feeds the sheets from the unit 5 to the unit 6 is raised to the position 41 illustrated in dotted lines which permits an operator to manually feed proof sheets to the unit 6 and as each unit may be

driven independent of the other, thus enables one man to make-ready the unit 5 and another the unit 6.

The advantage of simultaneous and independent make-ready for both units is obvious. It insures perfect impressions for each color as each plate prints on its own make-ready, and it reduces the time required for make-ready to that required for a single color. Thus with a two color press which has been rated as productive for 60% of the time, the simultaneous making-ready of both units would increase the time for actual printing to approximately 80% of the operating time.

The control for the starting and stopping of the drive motors 38 is diagrammatically illustrated in Figure 2.

When the bolts 36 of the clutch members are removed and the shafts 31 are free to turn with respect to each other so that each motor may drive its unit independent of the other, the position of the elements of the electrical control are as illustrated in Figure 2.

When it is desired to drive both units, at the same time, and to control the starting and stopping of their motors simultaneously, a switch 42 is closed which energizes a solenoid 43 by connecting it across feed lines 44 and 45 through conductors 46 and 47, the switch 42 being interposed in the conductor 47. Energization of the solenoid 43 attracts the armature 48 of a magnetic switch indicated generally by the numeral 49 and including normally open switches 50, 51, 52 and normally closed switches 53 and 54.

After the magnetic switch 49 is thus closed and the positions of the individual switches carried thereby reversed from that illustrated in Figure 2, the control is in such condition that all of the conventional push button controls of the both units effect both motors simultaneously.

The control for the motors includes magnetically closed switches 55 and 56, the switch 55 connecting the motor of the unit 6 across the lines when closed, and the switch 56 connecting the motor of the unit 5 across the lines. The closing of the switches 55 and 56 is independent upon the energization of their solenoids 57 and 58 respectively, and the energization of these solenoids in turn is brought about, when the control is set to simultaneously govern the operation of both motors, by the closing of either a push button start switch 59 mounted on the unit 6 or a similar switch 60 mounted on the unit 5. To break the circuit of the solenoids 57 and 58, push button stop switches 61 and 62 are provided.

It is, of course, understood that any number of start and stop switches may be positioned at various points about the units, but as this is conventional construction and does not enter into the invention, only one set of start and stop switches have been shown for each unit motor.

With the switch 42 open as illustrated, and the clutch members 34 disengaged from each other, closing of the push button start switch 60 will close the circuit of the motor of the unit 5 without effecting the motor of the unit 6. The circuit upon closing of the push button switch 60, beginning from the line 44, extends through conductor 63 to one side of the closed stop switch 62 through the switch 60 to its other side then through a conductor 64 to a terminal 65 of the switch 54.

From the terminal 65 the circuit continues through the closed switch 54 to its contact 66 from where a conductor 67 leads to one side 68 of the push button start switch 60. The switch 60 having been closed, carries the current across to its other side 69, which then passes through conductor 70 to one side of the solenoid 58, through the solenoid 58 to energize it, and to the line 45 through a conductor 71.

Upon energization of the solenoid 58 the magnetic switch 56 closes and connects the motor of the unit 5 across the lines 44 and 45 and also closes the switch 72. The switch 72, in closing, maintains the continuity of the circuit energizing the solenoid 58 to permit the push button start switch 60 to be released. The circuit for the solenoid 58 then extends from the side 68 of the open switch 60, through conductor 73 to the terminal 74 of the switch 72, through the closed switch 72, and to the other side 69 of the open start switch 60, through the conductor 75. From the point 69 the circuit is again completed by the conductor 70, the solenoid and the conductor 71.

The closing of the motor circuit of the unit 5 thus has no effect upon the control for the motor of the unit 6 which functions similar to that described in connection with the unit 5.

To actuate the control of the motor of the unit 6 the push button start switch 59 is closed which causes the solenoid 57 to be energized. The circuit of the solenoid 57 also begins with the line 44 and extends through conductor 76 to the contact 77 of the normally closed switch 58, through the switch 58 to its terminal 78, through conductor 79 to one side of the normally closed push button stop switch 61, and from its other side through conductor 80 to one side 81 of the push button start switch 59.

The switch 59 having been closed the circuit continues through the switch to its other side 82 and then through conductor 83 to one side of the solenoid 57, passing through the solenoid to energize it and being completed through conductor 84 to the line 45. As before, circuit of the solenoid is maintained independent of the push button start switch, by the closing of the switch 55 which closes a switch 85.

The circuit then extends from the side 81

of the now open switch 59 through conductor 86 to contact 87, through the closed switch 85 and to the other side of the switch 59, through conductor 88, from which point the circuit continues through the conductor 83 to one side 70 of the solenoid 57 and to the line 45 through conductor 84. To open the circuits of the solenoids 57 and 58 it is only necessary to depress their respective push button stop switches 61 and 62 respectively. 75

The control is maintained in this position throughout the make-ready, enabling each operator to control his unit entirely independent of the other, permitting him to start the machine, stop it and do whatever is necessary 80 during the process of the make-ready without effecting the similar work of the operator of the other unit. It is obvious that in this manner the time for make-ready of a two color press is reduced to that required for 85 a single color press and where more than two colors are used the time for make-ready is even further reduced.

After both units have been made ready 90 and the outer end 40 of the delivery mechanism of the unit 5 is again lowered to its position above the tape conveyor 17, it is necessary before the clutch members 34 are connected, to line up or put the two color units in step. This is necessitated by the fact that the drive shafts 31 travel at a greater speed than the plate and impression cylinders, and to facilitate the proper alignment of one unit 95 with the other, the impression cylinders of both units are provided with arrows 89 which align with arrows 90 on the adjacent portion of the frame 91 when the two units are in step. The bolts 36 may then be inserted to connect the clutch members 34. 100

After the clutch members are engaged the switch 42 is closed which as has been described, closes the magnetic switch 49 and reverses the positions of the switches 50, 51, 52, 53, and 54. When the control is in this condition the closing of either of the push button start switches 59 or 60, simultaneously closes the circuits of both solenoids 57 and 58 to connect both motors across the line. Considering that the switch 60 is closed the circuit for the solenoids 57 and 58 is as follows: 105

Again beginning with the line 44, the circuit extends through conductor 63, normally closed stop switch 62, conductor 64 to terminal 65, and the now open switch 54. The switch 54 having been opened, the circuit cannot follow the path previously described, but continues along conductor 92 to terminal 93 of the now closed switch 52, across the switch to its contact 94, then through conductor 95 to terminal 78 of the just opened switch 53. From the terminal 78 the circuit follows conductor 79 to the normally closed stop switch 61 the conductor 80 to the side 81 of the push button start switch 59 which however, has not been closed. The current 110 115 120 125 130

then follows conductor 98 to terminal 99 of the now closed switch 51.

Crossing the closed switch 51 to the contact 100 the circuit extends along conductor 101 to the side 68 of the push button start switch 60, which having been closed conducts the current to its other side 69 and then to the solenoid 58 in the manner previously described to energize the same.

From the side of the solenoid 58 with which the conductor 70 connects, the current passes along conductor 102 to contact 103 of the now closed switch 50, passing through the switch 50 to its terminal 104, then along conductor 105, and to the line 45 through conductor 84 as previously described.

Thus it will be seen that the closing of the switch 60 has energized both the solenoids 57 and 58, which in closing connect their respective motors across the line and also close their switches 85 and 72 respectively, to maintain the circuit of the solenoids independent of the switch 60. If the switch 59 is closed the same condition will take place, that is, both solenoids 57 and 58 will be energized.

When this is done, the circuit begins at the same point and extends along conductor 63 across the closed stop switch 62, conductor 64, conductor 92, switch 52, conductor 95, conductor 79, closed stop switch 61, conductor 80 to the side 81 of the switch 59. The switch 59 having been closed, the circuit continues through the switch to its other side 82 through conductor 83 to the solenoid 57 and then to the line 45 through conductor 84, to energize the solenoid. From the side of the solenoid 57 with which the conductors 83 and 105 are connected, the circuit also extends along conductor 105 to terminal 104 of the closed switch 50, through the switch 50 to its contact 103, from which the conductor 102 completes the circuit to the solenoid 58.

As the circuit for both solenoids 57 and 58 passes through both the stop switches 61 and 62 it is obvious that the opening of either one will interrupt the continuity of the circuit, and permit the switches 55 and 56 to be opened to disconnect both motors from the line.

In Figures 4 and 5 is illustrated a slightly modified manner of coupling the drive shafts 31. In this structure, the clutch members 34 are replaced by conventional jaw clutch members 106 and 107, the member 107 being fixed to its shaft 31 and the member 106 being slidably, but non-rotatably connected with its respective shaft.

Axial movement of the clutch member 106 to engage and disengage the member 107 is obtained by means of a handle 108 secured at its lower end to a transverse shaft 109 suitably journaled in bearing members 110. The inner end of the transverse shaft 109 has a shifter fork 111 secured thereto, which,

through a yoke member 112 received in an annular channel 113 of the hub of the member 106, imparts movement of the handle and the shaft 109 to the member 106.

The outermost bearing 110 has a segment 114 extended therefrom with which a member 115 cooperates to maintain the lever and consequently the jaw 106 in either of its two positions. The member 115 is yieldably engaged with the depressions of the segment 114 by an expansive spring 116 and is moved out of engagement with the depressions against the action of the spring by movement of the grip 117, in the customary manner.

The shaft 109 also has a lever arm 118 fixed thereto, the outer end of which is connected with the actuating arm 119 of a switch 120 which takes the place of the switch 42, so that actuation of the handle 108 to engage and disengage the clutch members automatically closes and opens the switch to place the electrical control in proper condition.

From the foregoing description taken in connection with the accompanying drawings it will be seen that I provide, a multi-color press which eliminates the major difficulties of make-ready, simplifies the design of such presses, and reduces the time required for make-ready to that required for a single color press.

What I claim as my invention is:

In a printing press, a plurality of printing units in end to end arrangement, each unit having a delivery mechanism arranged to feed the following unit, drive means including a motor for each unit, an electric control for the motors including a plurality of manually actuated switches, a switch incorporated within the electric control, one position of the switch placing the control in a condition whereby all of the manually actuated switches control all of the drive motors, and another position of the switch placing the control in a condition whereby the manually actuated switches of each unit effect only the drive motor of their respective unit, mechanical means for coupling the drive means of the units, and means whereby setting of the mechanical means simultaneously moves the switch within the electrical control to its position corresponding to the position of the means for coupling the drive means of the different units.

In testimony whereof I have hereunto affixed my signature.

FRANK R. BELLUCHE.
